UNITED STATES PATENT OFFICE.

RUDOLF VON FROMMER, OF BUDAPEST, HUNGARY.

CARTRIDGE MAGAZINE.

Application filed August 23, 1921, Serial No. 494,550, and in Hungary June 8, 1918.

As is well known, attachable cartridge magazines, adapted to receive a large number of cartridges, are of very great importance in connection with small firearms, such as the 5 repeating rifle, especially at certain periods of the fighting, still they have the disadvantage of resulting otherwise in much waste in the ammunition.

The subject of my present invention is a 10 cartridge magazine, adapted to receive a large number of cartridges which magazine can be adjusted however so as to deliver either all the cartridges or only a portion thereof, as wanted.

15 According to the present invention this is attained by providing a catch which protrudes into the path of the feederplate and which can be either inserted or withdrawn. This catch is so arranged, that when inserted 20 the feeder, after delivering a certain number of cartridges, (in most of the cases this will be the number, corresponding to the capacity of a usual loading frame) comes into touch with the catch and will be prevented thereby, to deliver those cartridges to 25 the breech, which are still left in the magazine while with the catch withdrawn, the feeder can deliver to the breech all the cartridges, which are in the magazine.

30 On the drawing one embodiment of my invention is shown by way of example.

Fig. 1 is a longitudinal section and

35 Fig. 2 the inner view of a part of the narrower side partition of the cartridge magazine.

The feederplate *b* of the cartridge magazine *a* is provided with a nose *e*, adapted to slide in the groove *d*, arranged in one of the narrow partitions *c* of the cartridge magazine. 40

In the projection *f* of partition *c*, there is

located an adjustable catch *g*, which by the aid of the knob *h* can be freely adjusted so as to project into the path of nose *e* (Fig. 1). In this case the feeding plate can proceed, only so far, until the nose *e* comes into engagement with the catch *g*. When however the catch is turned about an angle of 90 degrees (Fig. 2) and thus is withdrawn from the groove *d*, the nose *e* is allowed an unrestrained motion and the feeder can deliver all the cartridges, contained in the magazine. 45 50

The adjustable catch *g* is arranged in such a part of the side partition *c*, that the feeder from its lowermost position up to the shoulder, formed by the catch *g* will feed the wanted number of cartridges, which number in most cases corresponds, to that, received by the usual loading frame. 55

The arrangement, according to this invention, also serves to fix the feeder in the cartridge magazine, when the magazine is removed from the rifle, because otherwise in this case the feeder as well as its spring would jump out of the magazine. 60 65

Of course, it is possible to arrange more than one catch in the magazine should the feeding of more than two different sets of cartridges be wanted.

I claim as my invention:

An attachable cartridge magazine for rifles and similar fire-arms comprising, in combination with the feeder-plate and the feeder-spring acting upon the said feeder-plate, a movable catch for the feeder-plate 70 75 mounted on said magazine intermediate the ends of the stroke of the feeder-plate, and means for moving the catch into or out of the path of the said feeder-plate.

In testimony whereof I affix my signature.

RUDOLF VON FROMMER.
